BLOCK FOR PULLEY TACKLES

Ane Pieter Schat, Utrecht, Netherlands

Application May 3, 1937, Serial No. 140,513
In Germany May 8, 1936

2 Claims. (Cl. 254—195)

This invention relates to blocks for pulley tackles, more especially, but not exclusively, to blocks for tackles as used for handling life boats on board ships. Its principal object is to provide means whereby the standing part of the hoisting rope rovèn through the tackle blocks can be instantaneously released so as to allow kinks in the rope to be readily removed, and thereafter fixed again.

With this object in view, I suggest to fit the block, to which the standing part of the hoisting rope is to be secured, with a casing tapering in the direction of the load to which the block is to be subjected by the rope and housing a mating wedge member, said casing and said wedge member being adapted for sufficient lengthwise relative displacement to provide the required clearance for receiving the standing part of the rope passed around the thick end of the wedge.

As far as the operation of the block is concerned, either the casing or the wedge may be slidable relative to the block. In practice, however, it is preferred to make the wedge slidable and to rigidly secure the casing to the block. In that case, the wedge may lie loosely within the casing, but preferably it has a pin and slot connection therewith, so that it cannot get lost.

In order that my invention may be well understood, I shall now proceed to describe the same with reference to the annexed drawing, on which:

Fig. 1 is a side elevation, and

Fig. 2 is a front elevation of a pulley tackle, the top block of which embodies the invention, whereas

Fig. 3 is a side elevational view of a similar tackle, the running block of which is provided with means in accordance with the invention.

The pulley tackle shown in Figs. 1 and 2 comprises a top block 4 provided with one grooved pulley 5 rotatably mounted on a pin 6, and with an eye 7 from which the block can be suspended.

The running block, designated by 8, houses two grooved pulleys 9, 10 rotatable about a common pin 11 and has an eye 12 for engaging the load to be hoisted by means of the rope 13.

Secured to the outer side of the top block 4 is a casing 14 having side walls 14a, 14b tapering in the direction towards the running block 8. This casing houses a grooved mating wedge member 15 having a curved top and a vertical slot 15a which is engaged by the pin 6. In the lowermost position of wedge member 15, the clearance be-

tween the tapering walls thereof and those of the casing 14 is appreciably smaller, but in the uppermost position this clearance is greater than the diameter of the rope 13.

As shown, the standing or fixed part 13a of the rope 13 runs upwards between the wedge 15 and the side wall 14a of the casing 14, passes around the curved wedge top and runs downward between the wedge and the side wall 14b of said casing. It will thus be understood that, whenever the running block 8 is loaded, the tension in the standing part 13a acts to forcibly clamp in the bight of said part located between the wedge and the tapering side walls of the casing 14. If, for some reason, it is desired for the standing part 13a to be disengaged, for instance, for removing kinks in the rope 13, and assuming the running block 8 to be in unloaded condition, all that is required is imparting an upward blow to the wedge 15 so as to produce clearance between 20 the wedge and the tapering walls 14a, 14b whereby the standing part 13a can be released from the casing 14.

Fig. 3 illustrates a second embodiment, in which the top block 4 and the running block 8 house 25 three and two pulleys, respectively. The wedge 15 here is not mounted in the top block, but in the running block, in which it is fitted in the space intermediate the pulleys.

What I claim is:—

1. A block for a pulley tackle, comprising in combination a pulley, a pin on which said pulley is rotatably mounted, suspension means, a casing having walls tapering in a direction away from said means, and a wedge member fitted between 35 said walls and mating the same, said member having a slot engaged by said pin so as to be adapted for reciprocation in said direction between predetermined limits.

2. In a device of the character described a 40 block body, at least one pulley wheel therein, a casing carried with the body laterally of the wheel and provided with opposed walls tapering toward the outer edge of the block, a wedge member fitted between the walls of the casing and mating 45 the same and provided with a longitudinal slot, and a single pin traversing the body, pulley, casing and wedge member and serving to rotatably mount the pulley wheel in the block and slidably mount the wedge member in the casing within the 50 limits defined by the ends of the slot.

ANE PIETER SCHAT.
